UNITED STATES PATENT OFFICE.

CHARLES C. CAMPBELL, OF WASHINGTON, DISTRICT OF COLUMBIA.

SPARK PLUG.

Application filed March 8, 1927. Serial No. 173,720.

This invention relates to spark plugs, designed primarily for use in connection with that type of internal combustion engines or motors provided with sockets for the reception of the spark plugs and with these latter set in with respect to the outer face of the engine block, for example engines or motors of the Knight type, and the invention has for its object to provide, in a manner as hereinafter set forth, a spark plug so constructed and so arranged with respect to the engine block to overcome sparking or short circuiting at the outer end of the plug under such conditions providing for an efficient operation of the engine or motor.

In the motors of the type having the spark plugs set in with respect to the outer face of the engine block, it frequently happens that short circuiting is had at the outer end of the plug, due to the nearness of the engine block, which prevents the plugs firing in the combustion chamber, and to overcome such objection and to increase the efficiency of the engine is the aim of a spark plug, in accordance with this invention, and to this end the invention resides in arranging the outer terminals of the plugs the desired distance from the outer face of the engine block to prevent sparking at the outer ends of the plugs, under such conditions overcoming short circuiting with respect to the plugs.

Further objects of the invention are to provide, in a manner as hereinafter set forth, a spark plug for the purpose referred to which is simple in its construction and arrangement, strong, durable, thoroughly efficient in its use, readily installed, and inexpensive to manufacture.

With the foregoing and other objects in view the invention consists of a novel construction, combination and arrangement of parts as hereinafter more specifically described and illustrated in the accompanying drawings, wherein is shown an embodiment of the invention, but it is to be understood that changes, variations and modifications can be resorted to which fall within the scope of the claims hereunto appended.

In the drawings wherein like reference characters denote corresponding parts throughout the several views:

Figure 1 is an elevation, upon a reduced scale, of a spark plug in accordance with this invention.

Figure 2 is a vertical sectional view upon

an enlarged scale, of a spark plug in accordance with this invention.

Figure 3 is a section on line 4—4 Figure 2.

Figure 4 is a fragmentary view, in vertical section, of a modified form of plug.

Referring to the drawings in detail 1 generally indicates a metallic shell formed of an outer portion 2 and an inner portion 3. The outer portion 2 is of greater outer and inner diameters than the portion 3, whereby the latter is inset with respect to said outer portion 2. The inner portion 3 is provided with threads 4 for connecting the shell 1 to the engine block to secure the plug in position. The inner face of the outer portion 2 is threaded, as at 5. The outer part of said portion 2 is enlarged and of polygonal contour as at 6, to facilitate the securing and removing the shell 1 to and from the engine block. Formed integral with the inner end edge of the shell 1, is the outer electrode 7 which is of angle-shaped contour so as to extend towards the axis of the shell 1.

Arranged within and extended from the outer part 2 of the shell 1 is a core 8 of the insulation material, which is as well known, seats upon a shoulder formed at the point of joinder between the outer part 2 and inner part 3 of the shell 1. The core 8 is fixedly secured to the shell 1 by a peripherally threaded flanged collar or sleeve 9 which engages with the threads 5 of the shell 1 and has its inner end edge bear against the core 8 whereby the latter is fixedly clamped to the shell 1.

Extending axially through the core 8, as well as fixedly secured therewith is a central electrode 10 which projects from the inner end of the core 8 and also from the inner end of the shell 1 and coacts with the outer electrode 7. The central electrode 10 is of a length to project a substantial distance from the engine block to prevent sparking at the outer end of the plug to overcome short circuiting.

The central electrode 10 is formed of an inner section 11 and an outer section 12, which is of greater diameter than the section 11. The section 12 at its inner end is formed with a lengthwise extending socket 13 having a threaded wall with which engages the threaded outer terminal portion 14 of the section 11. The section 12 between its transverse median and its outer end is formed

with an annular flange 15, and that part of the section 12 exteriorly of the flange 15 is threaded as at 16 for engagement by an interiorly threaded cap member 17 to clamp 5 a circuit wire connection, not shown, to the flange 15, whereby the central electrode 10 is electrically connected with a source of energy. The cap member 17 preferably is constructed of insulation material.

10 The core 8 centrally thereof, is formed with an elongated socket 18 and a mortise 19 at the outer end of the socket 18. The socket 18 extends below the transverse median of the core. Seated throughout the socket 18 15 and extending from the core 8 to the section 12 of the central electrode 10, is a sleeve 20 of insulation material which closely envelopes the section 11 from the inner end of the socket 18 to the inner end of the section 20 12. The mortise 19 is formed in the outer end of the core 8, seated in said mortise and extending from the core 8 to the flange 15 is a sleeve 21 of insulation and which snugly 25 embraces the sleeve 20 and also a part of the section 12 of the electrode 10. The periphery of the sleeve 21 is flush with the edge of the flange 15 and the latter binds against the sleeve to fixedly secure it in position. The section 12 of the electrode 10 binds 30 against the sleeve 20 to secure it in position and the periphery of the sleeve 20 is flush with the periphery of that part of the section 12 in which is formed the socket 13.

35 The modified form shown in Figure 4, is the same as that illustrated in Figure 2, with this exception that the outer sleeve of insulation, indicated at 22 is mounted directly upon the outer end of the core 8 and does not extend into a mortise, as the core indicated at 23 is not provided with a mortise 40 for the reception of the inner end of the sleeve 22. Otherwise than that as stated the construction shown in Figure 4 is the same as that referred to in connection with 45 Figure 2.

The central electrode 10 is of materially greater length than the depth of the socket formed in the engine head in which the plug is to be mounted and of such length with 50 respect to the depth of the socket as to project a substantial distance from the mouth of the latter to prevent a sparking action at the outer terminal of the plug with respect to the outer face of the engine head, under 55 such conditions overcoming short circuiting, with respect to the plug, resulting in increased engine efficiency, therefore it is thought the many advantages of a spark plug, in accordance with this invention, can 60 be readily understood, and although the preferred embodiment of the invention is as illustrated and described, yet it is to be understood that changes in the details of con-

struction can be had which will fall within the scope of the invention as claimed.

65

What I claim is:

1. A spark plug comprising a metallic shell provided with an outer electrode, a core of insulation secured in the shell, a central electrode extending through the said core and projecting from the outer end thereof and formed with a flange adjacent to its outer end, a pair of concentrically arranged sleeves of insulation interposed between the flange and the core, the inner of the said sleeves having its inner end extended from the inner end of the outer sleeve and the outer end of the outer sleeve extending from the outer end of the inner sleeve.

2. A spark plug comprising a metallic shell provided with an outer electrode, a core of insulation secured in the shell, a central electrode extending through the said core and projecting from the outer end thereof and formed with a flange adjacent to its outer end, a pair of concentrically arranged sleeves of insulation interposed between the flange and the core, the inner of the said sleeves having its inner end extended from the inner end of the outer sleeve and the outer end of the outer sleeve extending from the outer end of the inner sleeve,

3. A spark plug comprising a metallic shell provided with an outer electrode, a core of insulation secured in the shell, a central electrode extending through the said core and projecting from the outer end thereof and formed with a flange adjacent to its outer end, a pair of concentrically arranged sleeves of insulation interposed between the flange and the core, the inner of the said sleeves having its inner end extended from the inner end of the outer sleeve and the outer end of the outer sleeve extending from the outer end of the inner sleeve, said central electrode formed of an inner and outer section connected together, said inner sleeve having its outer end abutting against the inner end of said outer section, and the said outer section extending from said outer sleeve and having its flange abutting against the outer end of the outer sleeve.
